Letters Patent

The schedule referred to in this Letters Patent and making part of the same, containing a description in the words of the said Henry Allen himself of his improvement in the Cotton Planter

To all to whom these Presents shall come -

Be it known, that J. Henry Allen, in the County of Lincoln and State of Tennessee has invented a new and useful cotton planter, and that the following is a full and exact description thereof -

I have a frame about seven feet long and as wide as may be deemed necessary for the ridge, about the middle of this frame are placed two wheels on the axle of which the frame rests, these wheels are about two feet in diameter and three or four inches thick and are confined to the axle which revolves with them, about the centre of this axle or shaft is placed a ^{square} wheel of two or three inches thickness and about six inches in diameter, round this wheel I place a box or hopper as large as may be found necessary resting on the frame and so cased inside as to form an aperture for the wheel, this aperture is extended two or three inches in front of the wheel, which is made to open or close at pleasure by a small rod and confined to a regulating gate completely filling the aperture and hung above by hinges, the other end passing through a cross bar of the frame with a screw tap on either side, in this way the soil may be dropped, thin or thick, at pleasure on the outside of the box or hopper are two rods or bars confined about the middle on either side, these bars are held upright so high as to admit a cross bar sliding upward and downward, pistons connected to each end, and connected to cords on the under side of the wheels making cranks, six or eight inches long, in this cross bar are confined two or three pistons running down and

the bottom of the hopper or box, the lower end of which may be enlarged or knuckle joints forcing the seed down upon the tooth wheel. This operation may also be performed by a conveyor working in an oblong box, under the hopper. At a convenient distance from the tooth wheel or dropper is formed a strong cross bar over which is confined a small shovel or bull tongue that opens the ridge, another cross bar in front of this carries the brace screw bolt of the bull tongue at the front end of the frame is a revolving axle with a wheel in the centre, which barely touches the top of the ridge when the planter is in operation, when the hind end of the frame is raised the dropping ceases and the planter is carried round on this axle & wheel to the next ridge, in the rear of this ground wheel is a cylinder box or twelve inches in diameter which is lowered out in the usual manner for covering the seed and breaking the clods, this cylinder is confined to the frame by two slats and a rod passing through the frame at the upper end and a rod around the frame at the lower end to assist in turning the planter.

The handles are made fast to the top of the frame braced and crossbarred at a convenient height, this machine is designed to open ridge drop the seed and cover them at one operation and may be worked by either horses or men.

What I claim as my invention and which I desire to secure by Letters Patent consists in the before described cotton planter.
